UNITED STATES PATENT OFFICE.

WILLIAM F. CAPITAIN, OF CHICAGO, ILLINOIS.

DESIGN FOR A FONT OF PRINTING-TYPE.

SPECIFICATION forming part of Design No. 16,104, dated May 26, 1885.

Application filed February 19, 1885. Term of patent 3½ years.

To all whom it may concern:

Be it known that I, WILLIAM F. CAPITAIN, a citizen of the United States of America, residing at Chicago, in the county of Cook and State of Illinois, have invented and produced a new and original Design for a Font of Printing-Type, of which the following is a specification, reference being had therein to the accompanying printed specimens.

10 My invention consists of a new design for a font of printing-type in which the letters and numerals are inclined backward at an angle of about twenty-five degrees, and are provided with ceriphs, and all the letters, characters, numerals, and ceriphs are formed of light lines of uniform thickness, and in which font there are no angularities in those portions of the letters which are usually curved.

15 The side lines of the letter A do not meet at the top, and the side lines of the letters V and W do not meet at the bottom, and the top of the letter A and the bottom of the letters V and W are formed of horizontal ceriph-lines

extended to the right and left beyond the bodies of these letters. The middle cross-lines of the letters A and H are V shape, the lines of which extend from the central angle upward to the right and left across and slightly beyond the side lines of these letters.

20 What I claim as new, and desire to secure by Letters Patent, is—

The design for a font of printing-type in which the letters are inclined backward, the upper ends of the side lines of A and the lower ends of the side lines of V, W are connected by horizontal lines extended beyond the side lines, the middle lines of A, H are V shape, extended across and beyond the side lines, these and the other portions of the design being as described and shown.

25 In testimony whereof I affix my signature in presence of two witnesses.

WILLIAM F. CAPITAIN.

Witnesses:

THOS. WILSON,
JAMES HAWKINS.
